UNITED STATES PATENT OFFICE.

ALBERT JOHN FORTESCUE, OF ARNCILFFE, NEAR SYDNEY, NEW SOUTH WALES,
AUSTRALIA.

MECHANICAL MOVEMENT.

1,111,569.

Specification of Letters Patent. Patented Sept. 22, 1914.

Application filed January 31, 1913. Serial No. 745,474.

To all whom it may concern:

Be it known that I, ALBERT JOHN FORTESCUE, a subject of the King of Great Britain, residing at Arncliffe, near Sydney, in the State of New South Wales, Commonwealth of Australia, have invented certain new and useful Improvements in Mechanical Movements, of which the following is a specification.

- 10 This invention relates to mechanical movements, and more particularly to variable gearing; and it proposes an improved gearing which is primarily designed for application to windmills, for the purpose 15 of utilizing an increase in wind force to transmit more power to the pitman rod and thus obtain greater efficiency, instead of tending to prematurely throw or veer the wind-wheel gradually out of operation.
- 20 According to the invention the variation in the force or power transmitted is effected through the operation of a comparatively small subsidiary wind wheel. This subsidiary wheel is suitably geared to a shaft 25 having a screw thread on which a threaded pillar carrying a slide is capable of traveling on rotation of the subsidiary wheel, the whole being carried on a rocking slide lever arm fulcrumed to an upright or frame 30 rigidly secured to the mill head piece. With this slide is pivotally connected an adjustable arm or rod which again is pivoted to a rocking arm also fulcrumed to the upright or frame above the rocking slide lever 35 arm. The shaft of the subsidiary wheel is provided with a suitable tension device, such as a coiled spring or weight, so that the tension thereof has first to be overcome before the wheel can rotate. The main 40 wind wheel gearing is coupled to the rocking slide lever arm preferably by means of a crank rod and pin. I prefer to use an endless chain and two sprockets, the chain being driven by a sprocket on the main 45 wind wheel shaft carrying the crank rod and pin. The crank rod engages with the rocking slide lever arm at the end near the pitman rod, oscillating same to effect reciprocation of the pitman rod which is pivoted to the aforesaid upper rocking arm.

The tension of the subsidiary wheel is so regulated that a moderate wind force has little effect thereon, but on an increase of force the tension is overcome and the 50 wheel revolved to rotate the screw shaft,

forcing the slide toward the pitman rod and the adjustable rod to take up a more vertical position with respect to it. The greater the wind force on the subsidiary wheel, the farther the slide is forced toward 60 the pitman rod and consequently a proportionately longer stroke is transmitted to it. When the wind force on the subsidiary wheel is reduced, the tension on the shaft reverses the motion and the slide and the 65 adjustable rod, are retracted, thereby obtaining a maximum transmission of power according to the wind force.

As a modification the adjustable arm or rod may be pivoted to the end of the pitman 70 rod and be provided with a friction wheel which bears against a rigid upright forming an adjustable fulcrum for the rod, the position of which fulcrum will vary in accordance with the wind force. But in order 75 that the invention may be clearly comprehended, I will now refer to the drawings herewith, in which,

Figure 1 is a general perspective view illustrating a windmill provided with my 80 improvements. Fig. 2 is an enlarged perspective view showing the variable gearing. Figs. 3, 4, and 5, are enlarged detail views. Figs. 6 and 7 are elevations, partly in section, showing the variable gear in different positions, the arrows indicating the extreme variations in the throw of the pitman rod. Fig. 8 is a similar view of a modification, illustrating the position of the adjustable arm or rod and pitman rod in a 85 normal wind.

The same numerals indicate like parts.

10 represents the tower of a windmill provided with the usual head 11 arranged to revolve in the tower cap 12 in suitable 95 bearings and carrying the gearing to obtain reciprocation of the pitman rod 36. I have shown chain and sprocket gearing 13 provided with the crank or wrist pin 14 and crank rod 15.

16 is the shaft of the main wind wheel. The reciprocating gearing of the main wind wheel may be of any type but I prefer that shown, the whole being set in a suitable gear case 17 and provided preferably with 100 automatic lubricators. The crank arm 18 on the upper end of rod 15 is connected to the rocking slide lever arm 19 fulcrumed to the frame 20 which is secured to the gear case or mill head piece 17. Carried 110

on said slide lever arm is the small wind wheel 22 mounted on a shaft 30 fixed on the wind wheel side of the carrying frame and connected by bevel gearing 23 to a screw shaft 24 rotatable in suitable bearings and provided with a screw nut 25 connected to pillar or post 26 which in turn is connected to the slide 27 capable of traveling along the arm 19 on rotation of the wheel 22.

I may use skew bevel, rack and pinion or other suitable gearing but I find that the screw gearing is best adapted to resist the consequent back thrust which takes place on the up stroke when the adjustable arm or rod 28 is at a sloping angle. The end of the slide 27 adjacent the pitman rod 36 has pivoted thereto the arm 28 which again is pivoted to a rocking arm 29 fulcrumed to the frame 20 above the rocking slide lever arm 19. On the shaft 30 of the wind wheel 22 is a guide reel 31 to which is fixed a flexible element 32, here shown as a rope which travels over a guide roller 33 or the like, and has suspended from it a suitable weight 34 or other device for obtaining the necessary tension. The weight is preferably disposed in a guide pipe 35 or in some other suitable manner.

37 is a fixed balancing vane to maintain the face of the main wind wheel 40 to the wind as described. The usual hinged tail vane 41 is also provided, but it is arranged so that it will not veer out of the wind so readily as in the usual windmill.

In operation, when the wind force is sufficient to overcome the weight 34 or other tension device on revolution of the wind wheel 22, the rope 32 is wound upon itself on the guide reel 31, each revolution requiring greater wind force to raise the weight (or to put more tension on the tension device). When the wind force diminishes, the weight descends, causing reversal of the wheel 22 accordingly. As the wheel raises the weight, it also, through the bevel gearing and screw, causes the slide 27 to be pushed out therefrom and consequently the adjustable arm 28 to be forced more toward the vertical, as shown in Fig. 7, and thereby greater efficiency is obtained by reason of the longer stroke. On reduction of the wind force to the normal, or below it, the adjustable arm is brought back to an angle of about 60° and the power of the main wind wheel is greatly increased by reason of the back leverage, the travel of the pitman rod and consequently that of the pump rod being less for each revolution of the main wheel than when the adjustable arm is about the vertical position. Although the back leverage is greater, the number of reciprocations of the pitman rod remains the same per revolution of the main wind wheel. The side movement of the pitman rod varies very

little from the vertical considering the great variation in the length of its stroke.

In Fig. 8 the adjustable arm 28 is pivoted to the pitman rod 36 and carries the friction wheel 42 which bears against the channel extension 43 of the frame 20, obtaining a variable fulcrum thereon.

44 represents a guide for the pitman rod. The positions which the adjustable arm may take up are similar to those shown in full and dotted lines in Figs. 6 and 7. In this form the pitman rod has an absolutely vertical travel.

Although I have illustrated the invention as applied to a windmill driven through chain and sprocket gearing I would have it understood that I do not restrict myself to any particular manner of oscillating the rocking slide lever arm.

It will be evident that instead of pivoting the adjustable arm or rod to the slide I may pivot it directly to journals on the traveling nut of the screw shaft in which case suitable friction wheels or other bearing devices are provided.

I claim:

1. In a mechanism of the character specified, the combination, with a rocking member, and operating means therefor; of a rotary driving member mounted upon said rocking member; a reciprocatory driven member, a device connected with said driving member for normally exerting tension thereon; a member slidable upon said rocking member and connected with said driving member for actuation thereby; and a rod carried by said slidable member and connecting the same and said driven member, for reciprocating the latter, whereby the movement of said slidable member will vary the angular position of said rod relative to said driven member to adjust the stroke thereof.

2. In a mechanism of the character specified, the combination, with a rocking member, and operating means therefor; of a rotary driving member mounted upon said rocking member; a reciprocatory driven member; a threaded shaft and a slide mounted on said rocking member; gearing connecting said shaft and said driving member; a traveling member mounted on said shaft and connected to said slide for shifting the slide during the rotation of said shaft; and a pivotally-mounted rod carried by said slide and connecting the same and said driven member, for reciprocating the latter, whereby the movement of said slide will vary the angular position of said rod relative to said driven member to adjust the stroke thereof.

3. In a mechanism of the character specified, the combination, with a main rotary driving member, a rocking lever, and connections between said main driving member

and said lever for operating the latter from the former; of a reciprocatory driven member toward which said lever extends; a subsidiary rotary driving member mounted on 5 said lever; a member slideable on said lever toward and from said driven member and connected with the subsidiary driven member for actuation thereby; and a rod carried by said slideable member and connecting the 10 same and said driven member for reciprocating the driven member, whereby the

movement of said slideable member will vary the angular position of said rod relative to said driven member to adjust the stroke thereof.

In testimony whereof I have hereunto set my hand in presence of two subscribing witnesses.

ALBERT JOHN FORTESCUE.
